COVER SPLASH GUARD FOR SINKS

David A. Pommiss, 7991 Sunrise Lakes Drive N.,
Fort Lauderdale, Fla. 33313

Filed Nov. 7, 1974, Ser. No. 521,588

Term of patent 14 years

Int. Cl. D23—02

U.S. Cl. D23—69

Fig. 1.

Fig. 4.

Fig. 2.

Fig. 3.

FIG. 1 is a top plan view of a cover splash guard for sinks showing my new design;

FIG. 2 is a bottom plan view thereof;

FIG. 3 is a side elevational view thereof; and
FIG. 4 is an isometric view thereof.

The broken line representation of a faucet fixture in FIG. 1, of a faucet fixture, a sink and a fragment of a counter top in FIG. 4 are for purposes of illustration only.

I claim:

The ornamental design for a cover splash guard for sinks, as shown and described.
